UNITED STATES PATENT OFFICE

155,918

DESIGN FOR A COMBINATION RADIANT AND CIRCULATING HEATER

Richard S. Moore, Dallas, Tex.

Application November 19, 1947, Serial No. 142,648

Term of patent 3½ years

(Cl. D81—19)

To all whom it may concern:

Be it known that I, Richard S. Moore, a citizen of the United States, residing in Dallas, in the county of Dallas and State of Texas, have invented a new, original, and ornamental Design for a Combination Radiant and Circulating Heater, of which the following is a specification, reference being had to the accompanying drawing, forming part thereof, in which:

Figure 1 is a side perspective view of a combination radiant and circulating heater, showing my new design. The other side, not shown, is substantially the same; and

Figure 2 is a front elevational view thereof.

I claim:

The ornamental design for a combination radiant and circulating heater, as shown and described.

RICHARD S. MOORE.
